(57) **CLAIM**

The ornamental design for a small compartments weighted blanket, as shown and described.

DESCRIPTION

FIG. 1 is a back side perspective view of a small compartments weighted blanket, showing my new design;

FIG. 2 is a back elevational view thereof;

FIG. 3 is a front elevational view thereof;

FIG. 4 is a right elevational view thereof;

FIG. 5 is a left elevational view thereof;

FIG. 6 is a back plan view thereof; and,

FIG. 7 is a top plan view thereof.

1 Claim, 7 Drawing Sheets
